UNITED STATES PATENT OFFICE.

GEORGE W. BLANKENHORN, OF SAN FRANCISCO, CALIFORNIA, ASSIGNOR TO CALIFORNIA PACKING CORPORATION, OF SAN FRANCISCO, CALIFORNIA, A CORPORATION OF NEW YORK.

PAPER-DISK SEPARATING AND FEEDING DEVICE.

1,407,318.

Specification of Letters Patent. Patented Feb. 21, 1923.

Application filed March 11, 1920. Serial No. 365,049.

To all whom it may concern:

Be it known that I, GEORGE W. BLANKENHORN, a citizen of the United States, residing at the city and county of San Francisco and State of California, have invented a new and useful Improvement in Paper-Disk Separating and Feeding Devices, of which the following is a specification.

This invention relates to a paper disk separating and feeding device, and especially to a device for delivering paper disks or blanks to a ring liner cutting and assembling machine, such as shown in my copending application entitled "Rolling cutter," filed August 15 28, 1916, Serial Number 117,188.

The application above referred to relates to an apparatus for cutting ring liners from a continuous paper web and applying the ring liners, when cut, to can ends. When cutting ring liners from a continuous web, it is obvious that for every liner cut a central core or blank is formed which would cause a considerable waste unless utilized. In actual practice I have found that the blanks produced may be re-used to great advantage for cans of smaller diameter and that the blanks again formed may be used for cans of still smaller diameter, thus reducing paper waste to a minimum.

The present invention is particularly designed to handle paper disks or blanks, and embodies a magazine or a holder for the reception of the same, a separating device, and means for feeding or delivering the blanks one by one to a series of cutting dies.

The invention also embodies other features which will hereinafter be more fully described, having reference to the accompanying drawings, in which—

Fig. 1 is a side elevation, partly in section, of a ring liner cutting and assembling machine, showing the application of the invention.

Fig. 2 is an end view of the paper blank holder.

Fig. 3 is an end view of the ring liner cutting and assembling machine showing the position of the feeding device; the feeding device shown being partially in section.

Fig. 4 shows a ring liner, together with the

interior blank and the exterior waste strip cut therefrom.

Referring to the drawings in detail, A indicates a base plate supported upon legs or standards 2. Suitably secured to the base plate is a frame 3, and journaled in said frame is a shaft 4, upon which is secured a die wheel 5. The die wheel is keyed to the shaft 4 and revolves in unison with the same; power being transmitted from any suitable source, not here shown, to impart a continuous rotary movement to the same. Pivotally mounted, as at 6, in the main frame 3 is an arm 7, on the outer end of which is formed a pair of bearing lugs 8; and journaled between said lugs is a roller or platen 9 which engages a pair of interspaced track members 10, formed on the die wheel.

Secured to the lower side of the base plate is a U-shaped bracket 11, and interposed between said bracket and the lower side of the arm 7 is a coil spring 12, the tension of which may be regulated by means of an adjusting screw 13. Suitably secured to the die wheel between the track members 10 is a plurality of annular cutting dies 14, and formed on the track members 10 are flattened portions 15, which align with the dies to permit the platen or roller 9 to practically engage the cutting edges of the respective dies.

The machine described in my copending application, referred to, is constructed in a manner very similar to the machine here shown. The paper stock employed, from which the ring liners were cut, was fed as a continuous web between the platen 9 and the cutting dies 14. This method of supplying paper caused considerable waste inasmuch as the cores or blanks formed by the cutting of the ring liners could not be reused with the paper feed there shown. The present invention has, therefore, been designed to utilize the blanks thus formed. This feed consists of a holder 16, in which is mounted three rods, such as shown at 17, 18 and 19. These rods extend upwardly on an angle and the paper disks are stacked between the rods, as shown at 20. Formed on the inner end of each rod is a stop member 21. These

stop members serve as supports for the entire stack of paper blanks and they also serve a second function, to-wit, that of separating the blanks one by one when removed 5 by a suction cup, such as shown at 22. This suction cup is mounted in such a manner that reciprocal movement may be imparted thereto, that is, its range of movement is shown in Fig. 1. It either assumes the full 10 line position shown, or the dotted line position shown.

This movement is transmitted in the following manner: Suitably secured in brackets 15 23, carried by the base plate, is a pair of guide rods 24, and slidably mounted on each guide rod is a cross head member 25. Connecting the cross head members is a cross- 20 wise extending rod 26, and adjustably secured thereon is a holder 27, through which extends a tube 28. Suitably secured on the upper end of the tube is a suction cup 22, and formed near the lower end of the tube is a vent opening 29, which is normally closed by means of a valve 30. This valve is pivot- 25 ally mounted, as at 31, in a bracket secured on the tube 28, and the valve is provided with a lever extension 32, which is adapted to engage a stop member 33. This stop member is adjustably attached to the bracket 11, 30 as indicated at 34, and its function will hereinafter be described. Secured to the lower end of the tube is a flexible rubber hose 35. This tube is connected with a vacuum pump or a similar device, not here shown.

Extending crosswise through the bracket 35 11 and journaled therein is a shaft 36, and secured on said shaft is a pair of crank arms 37. Connecting said crank arms with the cross shaft 26 is a pair of links 38, and se- 40 cured on one end of the shaft 36, is a crank arm 39 which is connected with a crank pin 40 by means of a link 41. The crank pin 40 is secured to a disk 42, which is secured on a shaft 43 supported in a journal member 44, and rotary movement is transmitted to 45 the shaft 43 from the main driving shaft 4, through a connected gear train, such as indicated at 45 and 46.

In actual operation, with power trans- 50 mitted to rotate the die wheel 5, it should be obvious that continuous rotary movement will be transmitted to the shaft 43 and the crank disk 42; similarly that an oscillating movement will be transmitted to the 55 shaft 36 through means of the link 4 and the crank arm 39. This oscillating movement is in turn transmitted through the crank arms 37 and the links 38 to the cross head members 25 and the cross rod 26 con- 60 necting the same, and as this rod supports the holder 27, the tube 28 and the suction cup 22, it should be obvious that a reciprocal movement will be transmitted thereto. The tube 28 supporting the suction cup passes

through a slot 7^a, formed in the arm 7, and 65 its angular position may be adjusted by turning the holder 27 upon the rod 26. That is, the holder is split, as indicated at 27^a, and a screw extending therethrough forms a means for tightening the holder in any angular 70 adjusted position. This adjustment is of importance as it permits vertical adjustment of the suction cup and the connected tube, and also angular adjustment of the same with relation to the end of the blank 75 holder and the platen 9.

With the suction cup in the position shown by dotted lines in Fig. 1, sufficient suction will be exerted to cause the foremost disk or blank in the stack 20 to adhere to the suction cup. This pulls the lower end of the blank away from the stop members 21 and also the upper stop member, indicated at 21^a. Forward movement of the holder, the tube 28 and the suction cup 22 brings the 85 cup, together with the blank adhering thereto, into position, directly in front of the platen 9 where the upper edge of the blank is engaged by the die 14 as this passes over the platen 9, as indicated by dotted lines at 90 20^a; the position indicated being that assumed when the blank is released by the suction cup. The stop member 33 engages the lever 32 a moment previous to assumption of the dotted line position indicated at 20^a and 95 thereby breaks the vacuum or suction in the cup 22 to such an extent that the blank is released, the release taking place the moment that the die 14 engages the upper portion of the blank. This release is, of course, 100 caused when the valve 30 opens the vent opening 29.

The die wheel, as previously described, rotates at constant speed and the blank delivered to the die will, therefore, pass between the die and the platen during the movement of the die over the platen and the ring liner is, therefore, cut from the blank during this operation and the waste produced is discharged from the machine in the direction of 110 arrow a. The suction cup is, in the meantime, moving back toward the blank holder and again assumes the dotted line position shown, where it removes the next blank. It then travels forward toward the platen and reaches this in time to deliver the blank to the next die. The dies 14 are equally spaced about the circumference of the die wheel and a certain time interval is thus permitted between each die. This time interval permitting one complete reciprocation of the feeder, a blank is, therefore, always in position as the die approaches the platen 9 and one complete reciprocation is transmitted to the feeder during the approach of each die. 120 125

The blanks employed are circular and may first be obtained when cutting ring liners for larger size can ends, and, for in-

stance, when employing a web feed, such as shown in my co-pending application referred to. These blanks shown in Fig. 4 are stacked, as indicated at 20, between the rods 5 17, 18 and 19. As these rods are inclined, it is obvious that they will settle downwardly toward the stop members 21 and 21^a, where they are held until removed one by one by means of the suction cup 22.

10 The stack of blanks gradually settles towards the stops referred to, first, due to the inclined position of the rods supporting the same, and, secondly, due to the slight vibration caused when the machine is in operation. The blanks, when delivered to the dies, are cut as shown in Fig. 4; that is, a ring liner is formed, such as shown at 50, which is retained by the die until it is transferred to a can end. A central blank 51 is 15 also formed and also an exterior waste strip 52. The central blanks are saved and may be reused for can ends of still smaller diameter; the holder employed for their reception being smaller than that shown in the 20 present instance as the diameter is reduced. The blanks may be cut down from one size to another until the smallest size can end is reached and paper waste is in this manner reduced to a minimum. The same feeding 25 device may be employed in each instance, the only change required being the substitution of a paper blank holder or an adjustment which permits the rods to be radially positioned as the size of the blanks decrease.

30 35 The importance of permitting adjustment of the suction cup should be obvious; that is, as the size of the blank decreases it should be obvious that adjustment of the suction cup should be permitted as it is desirable to 40 engage the blanks near the lower ends when removing the same from the stack. Engagement of the blank at the time of removal at a point near the lower end permits the blank to be pulled free; first, with relation to the lower stops 21; and, secondly, with relation to the upper stop 28. In other words, the foremost blank is gradually released with relation to the stops and ideal separation is thereby permitted. Adjustment 45 of the stop member 33 is also of importance as it permits suction release of the blank 20^a whenever desired.

50 The present feeding device is exceedingly simple as it avoids intermediate transferring means, registering means and other devices.

55 By referring to Fig. 1, it can be seen that the feeder removes the blanks from the stack in successive order and delivers them directly to the cutting dies, thus avoiding 60 the use of intermediate mechanisms such as are usually employed in feeding devices of this character.

While certain features of the present invention are more or less specific in design, I

wish it understood that various changes in 65 form and proportion may be resorted to within the scope of the appended claims; also that the materials and finish of the several parts employed may be such as the 70 experience and judgment of the manufacturer may dictate or varying uses may demand.

Having thus described my invention, what I claim and desire to secure by Letters Patent is—

75 1. A disk blank feeding device comprising a holder disposed on angle in which the blanks are adapted to be received in stack formation, a suction cup movable to and away from the stack on a horizontal line 80 adapted to remove the blanks one by one, and means permitting vertical adjustment of the suction cup with relation to the foremost blank in the stack and with relation to its horizontal line of travel.

85 2. A disk blank feeding device comprising a holder disposed on angle in which the blanks are adapted to be received in stack formation, a suction cup movable to and away from the stack adapted to remove the 90 blanks one by one, and means permitting angular adjustment of the suction cup with relation to the foremost blank in the stack.

95 3. A disk blank feeding device comprising a holder in which the blanks are adapted to be received in stack formation, a suction cup movable to and away from the stack adapted to remove the blanks one by one, and means permitting angular and vertical adjustment of the suction cup with relation to the foremost blank in the stack.

100 4. A disk blank feeding device comprising a holder in which the blanks are adapted to be received in stack formation, a member reciprocally mounted in front of the stack and movable to and away therefrom, a suction cup carried by said member adapted to remove the blanks one by one, and means permitting vertical and angular adjustment of the cup with relation to the reciprocating member in the foremost blank in the stack.

105 110 5. A disk blank feeding device comprising a holder in which the blanks are adapted to be received in stack formation, a plurality of stop members on the foremost end of the holder adapted to support the blank stack, a reciprocating member movable to and away from the stack along the axial line of the stack and on an angle with relation thereto, a suction cup carried by the reciprocating member engageable with the foremost blank in the stack adapted to pull it away from the stop members, and means for releasing the blank with relation to the suction cup.

115 120 125 6. A disk blank feeding device comprising a holder in which the blanks are adapted to be received in stack formation, said holder

being disposed on an incline, a reciprocating member mounted below and in front of the holder and travelling on a horizontal line, a suction cup carried thereby, said cup adapted to engage and remove the foremost blank when moved into engagement with the stack contained in the holder, and means for releasing the blank with relation to the cup.

7. A disk blank feeding device comprising a holder in which the blanks are adapted to be received in stack formation, a pair of guide rods mounted below and in front of the holder, a cross head member slidably mounted thereon, means for imparting a reciprocal movement to said cross head member to and away from the holder, a suction cup carried by the cross head member adapted to remove the blanks one by one from the holder, and means for releasing the blanks with relation to the suction cup.

8. A disk blank feeding device comprising a holder in which the blanks are adapted to be received in stack formation, said holder being disposed on an angle, a pair of guide rods longitudinally disposed mounted below and in front of the holder, a cross head member slidably mounted thereon, means for imparting a reciprocal movement to said cross head member to and away from the holder, a plurality of stop members on the holder engageable with the foremost blank in the stack, a suction cup carried by the cross head member engageable with the foremost blank in the stack and adapted to release it with relation to the stop members, means for breaking the suction in the cup to release the blank with relation to the cup, and means permitting vertical adjustment of the cup.

40 9. A disk blank feeding device comprising a holder in which the blanks are adapted to be received in stack formation, a pair of guide rods mounted below and in front of the holder, a cross head member slidably mounted thereon, means for imparting a reciprocal movement to said cross head member to and away from the holder, a plurality of stop members on the holder engageable with the foremost blank in the stack, a suction cup carried by the cross head member engageable with the foremost blank in the stack and adapted to release it with relation to the stop members, means for breaking the suction in the cup to release the blank with relation to the cup, and means permitting vertical and angular adjustment of the cup with relation to the cross head member and the foremost blank in the stack.

60 10. A disk blank feeding device comprising a holder in which the blanks are adapted to be received in stack formation, a pair of guide rods mounted below and in front of the holder, a cross head member slidably mounted thereon, means for imparting a

reciprocal movement to said cross head member to and away from the holder, a tube connected with a source of vacuum carried by the cross head member, means permitting angular and vertical adjustment of the tube with relation to the cross head member, a flexible suction cup on the upper end of the tube, a vent opening in the tube, and means for automatically opening and closing said vent opening.

11. A disk blank feeding device comprising a holder in which the blanks are adapted to be received in stack formation, a pair of guide rods mounted below and in front of the holder, a cross head member slidably mounted thereon, means for imparting a reciprocal movement to said cross head member to and away from the holder, a tube connected with a source of vacuum carried by the cross head member, means permitting angular and vertical adjustment of the tube with relation to the cross head member, a flexible suction cup on the upper end of the tube, a vent opening in the tube, a valve normally closing said vent opening, and an adjustable stop member adapted to automatically open and close said valve.

12. A disk blank feeding device comprising a holder in which the blanks are adapted to be received in stack formation, a pair of guide rods mounted below and in front of the holder, a cross head member slidably mounted thereon, means for imparting a reciprocal movement to said cross head member to and away from the holder, a tube connected with a source of vacuum carried by the cross head member, means permitting angular and vertical adjustment of the tube with relation to the cross head member, a flexible suction cup on the upper end of the tube, a vent opening in the tube, a valve normally closing said vent opening, an adjustable stop member adapted to automatically open and close said valve, and a plurality of stop members on the holder engageable with the foremost blank in the stack.

13. In a device of the character described, the combination with the cross head members and means for imparting a reciprocal movement thereto, of a cross rod connecting the cross head members, a holder adjustably mounted thereon, a tube mounted in the holder and a suction cup on the upper end of the tube.

14. A disk blank feeding device including an inclined holder in which the blanks lie in stacked formation, a pair of guides fixed with relation to the holder, a cross bar slidably mounted thereon and mechanism by which it may be reciprocated, a suction tube carried by the cross bar to be reciprocated therewith and having a mouth presented so as to be moved alternately into contact with the lowermost blank and withdrawn together

with the blank by the return movement, a valve carried by the suction tube and closable thereon, while the blank is being removed, and a stop fixed to engage and open 5 the valve at the end of the return movement.

In testimony whereof I have hereunto set

my hand in the presence of two subscribing witnesses.
